LIFE RAFT RELEASE

Harry Margolin, Brooklyn, N. Y., assignor to Over-board Equipment Corporation, New York, N. Y., a corporation of New York

Application April 15, 1944, Serial No. 531,206

9 Claims. (Cl. 9—41)

This invention relates to life raft launching devices and it has for its object, among others, to provide a device that is rigid and secure, but which quickly and surely launches a life raft into the sea from the deck of a boat by a simple manual control.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein—

Figure 1 is a side view of the invention.

Figure 2 is an enlarged detail of the releasing device.

Figure 3 is a rear elevation of Figure 1.

Figure 4 is an enlarged detail of releasing device (rear elevation).

Figure 5 is a plan view of Figure 1.

Figure 6 is an enlarged top detail of the releasing device.

Referring to Figures 1 and 3, the life raft support and launching device is preferably mounted on the deck A of a ship near one side thereof. The bottom of the device may be formed of two opposed L bars 10 and 10a connected at the rear ends by a cross L bar 11, at the front by a cross L bar 12 and an intermediate cross L bar 13 and such diagonal bracer (not shown) as devised for strength and rigidity, and may rest on the deck A. The parts may be suitably secured together by welding, rivets, or bolts. Two vertical L bars 14 and 15 are rigidly secured to, near but somewhat removed respectively from the opposite ends of the cross bar 11, and near to, but below the top, they are tied together, by an L cross bar 16, and still nearer the top, by another L cross bar 17. A diagonal brace 18 seats at the bottom in the L cross bar 13 and is secured at the top to the upright L bar 14. Similarly a diagonal brace 19 also seats at the bottom in the L cross bar 13 and is secured at the top to the upright L bar 15. Additional similarly secured diagonals 20 and 21 may be employed to enhance the strength and rigidity, as well as transverse back diagonals 22 and 23, broken away centrally as shown in Figure 3.

The top or raft support proper is mounted to swing from the full-line position to the dotted

line position, as shown in Figure 1. The top is rectangular in form and comprises two opposed side L bars 24 and 25, a front L bar 26 and a rear L bar 27. Four corner plates 28, 29, 30 and 31, and two diagonals, 32 and 33, secured at the front to corner plates 28 and 29 respectively and at the rear to top cross bar 27, both strengthen the top and provide rests for a raft which is supported thereon. A short L clip 34 on the side bar 24 mounts a bolt 35 extending transversely through the bar 24 and on which is pivotally mounted the lower end of the upright 36, the upper end of which is pivoted on the bolt 37 transversely mounted in an L clip 38 secured to and dependent from the side bar 24. The upright 36 proper is a U-bar having plates 39 secured at each end by locking U-plates 40.

Diametrically opposed and mounted on the right side bar 10a by another bolt 41 and clip 42 is another pivotally mounted upright 43, similar to upright 36, pivoted at the upper end on the bolt 44 which extends laterally from the top side bar 25 by means of an L-clip 45 depending from the top side bar 25.

Towards the front a U-bar 46, similar in construction to the U-bar 36, but longer, is pivoted on the left side bar 10 by a bolt 47 and an L clip 48 at its lower end, and at its upper end, by a bolt 49 and a clip 50, the U-bar 46 is pivoted on the rear end of the top side bar 24.

Diametrically opposed is a U-bar 51, similar in construction to the U-bar 46, pivoted on the right side bar 10a by a bolt 52 and an L clip 53 at its lower end, and at its upper end, by a bolt 54 and a depending clip 55.

Mounted on the bar 46 is a lateral stop plate 56 and on the bar 51 a similar but oppositely positioned stop plate 57 so positioned that when the top is released the bars 36 and 46 and 43 and 51 take the launching position shown in dotted lines in Figure 1.

Depending from the top front cross bar 26 near each end are depending L plates 58 and 59 and pivoted respectively below the bar 26 to the base plates are two longer bars 60 and 61 which rise above the bar 26 and so provide two retaining uprights at the front to hold the raft but tiltable to the downward position shown in dotted lines in Figure 1.

A cable 62 passes through holes in the bar 26 and over the front edges of the plates 58 and 59, which may mount a retaining padding, to normally hold the stop bars 60 and 61 in the upright position, and the ends are tied to a thimble 63. A turnbuckle 64 connects the thimble 63 with a

hook 65 at the rear. If the hook 65 be released the cable 62 falls and releases the stops 60 and 61.

The top cross bar is engaged by a latch 66, which locks the top platform by bar 27 against forward movement, in cooperation with the hook 65, and which depends from the rocker 67 which is pivoted at 68 in a pair of vertical rear plates 69 and 70, mounted on the rear cross bars 16 and 17. A transverse pin 71 extends through the rocker 67 at the rear and pivotally mounts two links 72 and 73 which extend forward under the bar 17 and are pivoted on opposite sides of a bar 74 on a pin 75. The bar 74 is weighted at the rear end 76 and is pivoted centrally on a bolt 77 secured in the plates 69 and 70, and mounts under the bolt 77 a depending handle 78. Clips 79 mounted on the rear end of a raft (not shown) may engage under the top of the top rear cross bar 27. A pin (not shown) may be passed through holes 80 in the bottoms of the plates 69 and 70 to lock the handle 78 against rearward motion, and so the entire tripping devices if desired.

As shown in Figures 2 and 4, a swivel 81 mounted between plates 69 and 70 above the rocker 74 on a bolt 82 mounts a radial pin 83 which engages a recess 84 in the top of the rocker 74, by which it is secured, in the locked position of the latch 66, against movement, and about which the rear end of the hook 65 is locked. The rocker 74 may be actuated also by a cable (not shown) depending from the front end, at 85; or/and a cable (not shown) may be secured at 86 to the bottom of the handle 78. Moving the rocker 74 by a cable or the handle 78 lifts the weight 76, the latch 66, and withdraws the pin 83 whereupon the top moves forward, and the locking uprights swing forward, until the raft is launched by gravity over the side of the deck A.

Having thus described my invention, what I claim is new and desire to secure by Letters Patent is:

1. A life raft launching device adapted to be mounted on the deck of a boat at one side thereof comprising in combination, a tiltable platform, a frame, supporting bars pivoted on the frame and also pivoted on the platform, a lock engageable with said platform and mounted on said frame, and means on the frame for releasing said lock.

2. A life raft launching device adapted to be mounted on the deck of a boat at one side thereof comprising in combination, a tiltable platform, a frame, supporting bars pivoted on the frame and on the platform, a lock engageable with said platform and mounted on said frame, means on the frame for releasing said lock, an upright on the end of the platform for retaining a raft thereon, and means on the frame for moving said upright to release said raft.

3. A life raft launching device adapted to be mounted on the deck of a boat at one side thereof comprising in combination, a tiltable platform, a frame, supporting bars pivoted on the frame and on the platform, a lock engageable with said platform and mounted on said frame, means on the frame for releasing said lock, an upright on the end of the platform for retaining a raft thereon, and means on the frame for moving said upright to release said raft, and means for simultaneously actuating said releasing means and said upright moving means.

4. A life raft launching device adapted to

be mounted on the deck of a boat at one side thereof comprising in combination a base having two parallel side angle bars, a back rigidly mounted on the rear ends of said bars, a platform having two parallel side angle bars, a pair of bars pivoted at their bottoms one on each base side bar, said pair of bars being pivoted at their tops one on each platform side angle bar, said pair of bars being symmetrically disposed with the tips in front of the bottoms, another pair of bars pivoted at their bottoms one on each base side bar but in front of said first pair of bars, the tops of said last pair of bars pivoted at their tops one on each platform side bar at the rear, and stops on said last pair of bars engageable in a tilted position of the platform with said first pair of bars to limit the tilting of the platform.

5. A life raft launching device adapted to be mounted on the deck of a boat at one side thereof comprising in combination a base having two parallel side angle bars, a back rigidly mounted on the rear ends of said bars, a platform having two parallel side angle bars, a pair of bars pivoted at their bottoms one on each base side bar, said pair of bars being pivoted at their tops one on each platform side angle bar, said pair of bars being symmetrically disposed with the tips in front of the bottoms, another pair of bars pivoted at their bottoms one on each base side bar but in front of said first pair of bars, the tops of said last pair of bars pivoted at their tops one on each platform side bar at the rear, and stops on said last pair of bars engageable in a tilted position of the platform with said first pair of bars to limit the tilting of the platform, a lock for said platform mounted on said rigid back, and a rocker arm for actuating said lock.

6. A life raft launching device adapted to be mounted on the deck of a boat at one side thereof comprising in combination a base having two parallel side angle bars, a back rigidly mounted on the rear ends of said bars, a platform having two parallel side angle bars, a pair of bars pivoted at their bottoms one on each base side bar, said pair of bars being pivoted at their tops one on each platform side angle bar, said pair of bars being symmetrically disposed with the tips in front of the bottoms, another pair of bars pivoted at their bottoms one on each base side bar but in front of said first pair of bars, the tops of said last pair of bars pivoted at their tops one on each platform side bar at the rear, and stops on said last pair of bars engageable in a tilted position of the platform with said first pair of bars to limit the tilting of the platform, a lock for said platform mounted on said rigid back, and a rocker arm for actuating said lock, an upright pivoted on the front of the platform and tiltable downwards, means for locking said upright against tilting and means for releasing said upright lock.

7. A life raft launching device adapted to be mounted on the deck of a boat at one side thereof comprising in combination a base having two parallel side angle bars, a back rigidly mounted on the rear ends of said bars, a platform having two parallel side angle bars, a pair of bars pivoted at their bottoms one on each base side bar, said pair of bars being pivoted at their tops one on each platform side angle bar, said pair of bars being symmetrically disposed with the tips in front of the bottoms, another pair of bars pivoted at their bottoms one on each base side bar but in front of said first pair of bars, the tops

of said last pair of bars pivoted at their tops one on each platform side bar at the rear, and stops on said last pair of bars engageable in a tilted position of the platform with said first pair of bars to limit the tilting of the platform, a lock for said platform mounted on said rigid back, and a rocker arm for actuating said lock, an upright pivoted on the front of the platform and tilttable downwards, means for locking said upright against tilting and means for releasing said upright lock, said upright locking means comprising a cable which also locks the platform against tilting.

8. A life raft launching device adapted to be mounted on the deck of a boat at one side thereof comprising in combination a tilttable platform, a rigid frame, supporting bars pivoted on the frame and on the platform, an upright pivoted

5 to swing below the platform at the front thereof, a cable for holding said upright above the platform and for holding said platform against tilting and means for releasing said cable mounted on the frame.

9. A life raft launching device adapted to be mounted on the deck of a boat at one side thereof comprising in combination a tilttable platform, a rigid frame, supporting bars pivoted on the 10 frame and on the platform, an upright pivoted to swing below the platform at the front thereof, a cable for holding said upright above the platform and for holding said platform against tilting and means for releasing said cable mounted 15 on the frame, said last means including a swiveled pin holding said cable in the locked position.

HARRY MARGOLIN.
